UNITED STATES PATENT OFFICE.

HENRY SIEBEN, OF KANSAS CITY, MISSOURI.

WASHING MACHINE.

1,411,750.

Specification of Letters Patent. Patented Apr. 4, 1922.

Application filed October 11, 1920. Serial No. 416,098.

To all whom it may concern:

Be it known that I, HENRY SIEBEN, a citizen of the United States, residing at Kansas City, in the county of Jackson and State of Missouri, have invented certain new and useful Improvements in Washing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to washing machines and more particularly to one wherein articles to be cleansed are rubbed and pressed against the rubbing surface by a vertically reciprocatory and rotatable agitator.

Fig. 1 is a view partly in elevation and partly in section of a washing machine constructed in accordance with my invention.

Fig. 2 is a similar view at right angles to the view shown in Fig. 1.

Fig. 3 is a sectional view through the driving gear for the mangle and wringer.

Fig. 4 is a sectional view through the main driving gear, showing the manner of driving the mechanism for the wringer and mangle shaft.

Fig. 5 is an enlarged detail view of the clutch mechanism for connecting the agitator drive to the main drive.

Fig. 6 is a detail view of the agitator reciprocating and rotating means.

Fig. 7 is a sectional view on the line 7—7 of Fig. 3, and

Fig. 8 is a detail perspective view of the agitator.

Fig. 9 is a detail view of one of the notched lock projections, and

Fig. 10 is a fragmentary perspective view of one of the steam conduits.

Referring now to the drawings by numerals of reference:

1 designates a clothes receptacle supported upon a suitable frame consisting of the top 2, the bottom 3, verticals 4 and diagonals 5, the base or bottom 3 being preferably supported upon castors 6 to render the machine

easily portable. The receptacle 1 is fastened to the top beam 2 of the frame in any suitable manner and beneath the same and secured to the frame is a burner 7 by means of 55 which the water within the receptacle 1 may be heated.

Suitably supported above the bottom of the receptacle 1 is a false bottom or rubbing surface 8, shown as consisting of a concavo convex disk, inclined from the periphery toward the center, the central portion being formed with a perforate, semi-spherical or substantially semi-spherical dome 9, which is perforated to permit the suds to drain back 65 into the sediment chamber formed by the space between the bottom of the receptacle 1 and the false bottom 8.

The false bottom is also provided with radial ribs or corrugations 10, as clearly indicated in Fig. 1.

Extending vertically along the inner wall of the receptacle 1 are spaced steam conduits 11, preferably V-shaped in cross section, the portions extending above the false 75 bottom 8 being provided with perforations 12 whereby steam and boiling water from the sediment chamber 13 may be directed up over the clothes within the upper chamber 14.

Extending through the top 15 of the receptacle 1 is a vertical shaft 16, which carries the agitator 17, to be specifically referred to hereinafter. The shaft 16 is provided with a cylindrical portion 18 having a groove 19 of relatively deep pitch, which is guided 80 in a loop 20 on a bracket 21 carried by the top 15 of the receptacle 1. There is a pin or projection 22 extending through the loop 20 and into the groove 19 so that when the shaft 16 is reciprocated, the pin 22 will ride 85 in the groove 19 and cause a rotative movement to be imparted to said shaft 16, as will be apparent hereinafter.

Mounted upon the shaft 16 is a yoke-shaped actuator 23, the upper lateral arm 95 24 of which constitutes a bearing for the upper end of the shaft 16, there being a spring 25 interposed between the arm 24 and the upper end of the barrel 18. The lower arm 26 of the yoke-shaped member 23 100 also constitutes a bearing for the shaft 16.

The lower end of the vertical arm 27 of the

yoke-shaped member 23 is provided with an elongated slot 28, in which rides a roller 29 on a link 30, mounted upon a shaft 31, journaled in a bearing casting 32 on the top 15. The shaft 31 is provided with a sliding clutch member 33, between which and the casting 32 is a coil spring 34, normally tending to move the clutch member 33 into engagement with a clutch member 35 on a drive shaft 36 10 driven by appropriate mechanism from the motor which supplies the power.

The clutch member 33 can be withdrawn out of engagement with the clutch member 35 by the pivoted lever 37, the eccentric end 15 38 of which is connected to the link 39 in engagement with the member 33. Therefore, when the lever is thrown into the position shown in Fig. 5, the clutch member 33 will be withdrawn from engagement with 35 but 20 when it is swung from left to right to permit the spring 34 to expand, the two clutch members 33 and 35 will be clutched together. Therefore, the shaft 31 will be driven. The shaft 31 is connected to the link 30 so that 25 as the shaft 31 is rocked, the roller 29 will move in slot 28 and cause an up-and-down movement to be imparted to the yoke-shaped member 23, consequently imparting an up-and-down movement to the shaft 16, and 30 through the medium of the cylinder 18, slot 19 and pin 22, an oscillatory movement will be imparted to the shaft 16 so as to impart a corresponding movement to the rubber 17 carried thereon. The rubber 17 is shown as 35 comprising a perforate disk having a plurality of convexities 40, in spaced relation between the perforations 41 and in co-operation with the false bottom 18, which constitutes the rubbing surface so as to loosen the dirt from the clothes. The shaft 36 is provided with a crank 42, connected by a link 43 to a crank 44 on the shaft 45, rigid with the gear 46 in the case 47. The gear 46 meshes with a gear 48 on a shaft 49 provided 45 with a pulley 50, aligning with the pulley 51 on the drive shaft 52 of the motor 53 and motion is communicated from the pulley 51 to the pulley 50 through a belt 54. The motor 55 is supported upon a slide 55 in guides 50 56 on the bottom of the frame which supports the clothes receptacle and there is a tension spring 57, one end of which is connected to the slide and the other anchored to one of the bars of the lower portion of the 55 frame so that there will be a normal tendency to pull the slide away from the pulley 50 to maintain the belt taut under all conditions.

When the motor is operating and the 60 shaft 45, through its gearing, is rotated, the link 43 will impart a rocking motion to the crank 42, imparting a corresponding motion to the shaft 36 so that the yoke-shaped member 23 will be reciprocated vertically when

the clutches 33 and 35 are together and an oscillatory motion will be imparted to the rubber 17.

The shaft 45 which carries gear 46 also carries a beveled gear 58, which meshes with a beveled gear 59 on the shaft 60 in the gear case 61. The shaft 60 (Figs. 3 and 4) drives a beveled gear 62 meshing with opposite gears 63 and 64 which, in turn, mesh with a gear 65, all of the gears rotating when the gear 60 rotates. The gears 62 and 65, however, are normally loose on the shaft 60 and either is adapted to be directly driven from the shaft 60 through a double-faced clutch 66, as will be well understood by reference to Figs. 3 and 7, the shifting of the clutch being effective in causing a reversal of rotation of the shafts 67 and 68 connected to the gears 63 and 64.

The shaft 67 is adapted to drive a mangle shaft 69 when the clutch 70 is moved into engagement with the pin or clutch member 71. If the clutch member 72 on shaft 68 is moved into engagement with the clutch member or pin 73 on the wringer shaft 74, the wringer rolls will be driven. The wringer is generally designated 75 and is of ordinary construction except insofar as it is adapted to be driven through the shaft 74. The clutches 70 and 72 are adapted to be alternately moved into engagement with their respective clutch members through the medium of a yoke-shaped actuator 75, which has downwardly projecting arms 76 and 77 passing through slots 78 and 79 (see Fig. 3), in a casing 80.

The yoke-shaped member is adapted to be operated through the medium of a handle 81, pivoted thereto, which may swing down into engagement with the notches 82 and 83 so as to hold the actuator in the extreme of two positions; that is, when the yoke-shaped actuator is moved in one direction to throw the mangle into operation, the wringer will be out and vice versa, and in either position, the handle 81, entering either of the notches 82 or 83, will constitute a lock. This is an important feature of my invention.

The receptacle 1 may be provided with a blow-off valve, conventionally shown at 84 (Fig. 2).

It will be apparent that when the parts are assembled the clothes will be subjected to the action of steam or hot water as well as a reciprocating and oscillatory rubbing motion so as to completely eliminate dirt and extraneous matter from the fabric, the rubbing action, however, being entirely mechanical.

It will also be apparent that the shape of the agitator is such that the cups constitute vacuum recesses, tending to create a suction when in operation and thereby facilitate the removal of the dirt from the fabric.

What I claim and desire to secure by Letters-Patent is:—

In a washing machine, a clothes receptacle, a false bottom in the receptacle forming upper and lower chambers therein and comprising a plate inclined downwardly from the sides of the receptacle toward the

center, the plate formed with an upstanding dome at its center, having perforations through which contents of the upper chamber may drain to the lower chamber. 10

In testimony whereof I affix my signature.

HENRY SIEBEN.
